UNITED STATES PATENT OFFICE

152,441

DESIGN FOR A TUB FILLER WITH TRANS-
FER UNIT FOR DIVERTING WATER TO
SHOWER

Amy Lenore Thomssen, Toledo, Ohio, assignor to
Barnes Manufacturing Co., Mansfield, Ohio, a
corporation of Ohio

Application April 30, 1947, Serial No. 138,728

Term of patent 14 years

(Cl. D4—3)

To all whom it may concern:

Be it known that I, Amy Lenore Thomssen, a citizen of the United States, residing at Toledo, in the county of Lucas and State of Ohio, have invented a new, original, and ornamental Design for Tub Filler with Transfer Unit for Diverting Water to Shower, of which the following is a specification, reference being had to the accompanying drawing, forming part thereof.

The figure is a perspective view of a tube filler with transfer unit for diverting water to shower, showing my new design.

I claim:

The ornamental design for a tub filler with

transfer unit for diverting water to shower, as shown.

AMY LENORE THOMSSEN.
